(57) **CLAIM**

The ornamental design for a combined kettle and pedestal, as shown and described.

DESCRIPTION

FIG. 1 is a front perspective view of a combined kettle and pedestal showing my design.

FIG. 2 is a front perspective view of the kettle in FIG. 1.

FIG. 3 is a rear perspective view of the kettle in FIG. 1.

FIG. 4 is a front elevation view of the kettle in FIG. 1.

FIG. 5 is a rear elevation view of the kettle in FIG. 1.

FIG. 6 is a left side elevation view of the kettle in FIG. 1.

FIG. 7 is a right side elevation view of the kettle in FIG. 1.

FIG. 8 is a top plan view of the kettle in FIG. 1.

FIG. 9 is a bottom plan view of the kettle in FIG. 1.

FIG. 10 is a front perspective view of the pedestal in FIG. 1.

FIG. 11 is a rear perspective view of the pedestal in FIG. 1.

FIG. 12 is a front elevation view of the pedestal in FIG. 1.

FIG. 13 is a rear elevation view of the pedestal in FIG. 1.

FIG. 14 is a left side elevation view of the pedestal in FIG. 1.

FIG. 15 is a right side elevation view of the pedestal in FIG. 1.

FIG. 16 is a top plan view of the pedestal in FIG. 1; and,

FIG. 17 is a bottom plan view of the pedestal in FIG. 1.

The broken lines in the drawings show portions of the combined kettle and pedestal that form no part of the claimed design.

1 Claim, 17 Drawing Sheets
